UNITED STATES PATENT OFFICE.

ROYCE L. BEERS, OF DETROIT, MICHIGAN, ASSIGNOR, BY MESNE ASSIGNMENTS, TO RILEY STOKER CORPORATION, OF WORCESTER, MASSACHUSETTS, A CORPORATION OF MASSACHUSETTS.

REAR-END STRUCTURE FOR REAR-DUMP STOKERS.

Application filed June 16, 1922. Serial No. 568,798.

In the construction of underfeed stokers of the rear-dump type, and particularly the multiple-retort stokers of this type, the structure and arrangement of the rear end of the fire-box floor upon which, normally, live fuel is being carried, must meet exacting requirements; and it is to the provision of a simple, efficient, durable rear-end structure that my invention is primarily addressed.

10 In an underfeed stoker wherein the fuel impelled longitudinally along the parallel retorts which have their tuyère bordered margins or mouths down-sloping toward the rear, for ultimate delivery of the refuse of combustion to an ash-pit beyond the end of the non-dumping portion of the fire-box floor, particularities of construction of the "rear-end structure" or portion of such fire-box floor intervening between the rear margin of the retort-body and the ash-dump space, are important to effective performance of the stoker. Across this rear end area the fuel has burned down so that the fuel mass handled by the rear end structure is apt to be 15 in a state of very active combustion, with even its ash-constituents in a highly heated state, so that the rear-end structure is subjected to trying conditions of use. Further, its construction has to do both with the functions of fuel-retardation, effecting performance along the entire longitudinal line of the retorts, and with the function of delivery of ash or of partly consumed fuel to the dumping area back of such rear-end.

20 Among the further objects of my invention, aimed to meet the severe demands upon this portion of the stoker construction, are the provision of sectional structures, with the sections in such mutually-effective units that deterioration may be very slow, but that replacement of burned out units may be 25 easily and inexpensively made; also to provide structural units of advantageous construction and inter-relation from the standpoint of manufacture and initial installation; also to provide for cooperation of the rear end structure with the retort body and tuyère elements separating adjoining retort bodies, for most advantageous functioning 30 of the stoker entity.

Other and further objects will become apparent to those skilled in the art from the following description taken in conjunction with the accompanying drawings wherein I

have illustrated a single embodiment of my 55 invention in its preferred form for purposes of full disclosure, although it will be understood that many changes in details of construction and arrangement may be made without departure from the spirit of my invention within the scope of the claims that are hereto appended.

In said drawings, Fig. 1 is a sectional view on line 1—1 of Fig. 2 with parts in elevation, showing sectionally the ridge portion of the 60 rear end structure of a stoker in association with fragmentary portions of known retort elements, dumping means and fuel-distribution means; Fig. 2 is a plan view of parts of the stoker shown in Fig. 1; Fig. 3 is an enlarged view of a rear end bottom plate and associate parts; Fig. 4 is a plan view of the 65 plate element of Fig. 3 and Fig. 5 is a section on line 5—5 of Fig. 3.

In the drawings 10, 10 indicate retort-bodies of known construction, extending in parallelism to receive fuel from feed rams, not shown, of usual provision, arranged beyond the front (left) ends of the retorts. The 70 rearwardly down-sloping margins 11 of the parallel retorts are spanned by tuyère structures 12, extreme retorts of a series having their outer walls surmounted by suitable tuyère structures 12' extending to the furnace-sidewall 13. Each retort body, in the 75 particular construction illustrated, may have a horizontal bottom portion 14, over which works a distributor or pusher block 15, ram-actuated in known fashion, and the horizontal bottom portion may merge into an up- 80 sloping body-end 16 terminating in a flange 17, with which the rear-end structure to be described may coact. The main tuyères 12 and 12' preferably terminate in the neighborhood of the body-end 17, preferably slightly 85 forward of the flange. The retort bodies may be positioned on a suitable frame structure typified by beam 18, and the rear-end structure to be described may find support 90 between the flanged ends of the retort bodies and a suitable frame member such as the transverse beam 19 which, with its foundation 95 20 may form part of a partition wall dividing an air chamber 21 underlying the non-dumping structure of the fire-box floor 100 from an ash-pit 22 which underlies the ash-dump structure illustrated at 23.

The rear end of each retort-body has an

upwardly opening channel 24. An angle bar 25, with its flange up-turned, is bolted as at 26 to the under side of the end-flange 17 of each retort-body, to afford such a channel, as shown. A single angle bar 25 extending full width of the stoker may be employed, for strength, in affording the channels for all of the respective retorts and between this angle bar and the top surface 19' or the transverse frame member 19 the rear-end structure may be supported in self-locking arrangement. In general, such rear-end structure is shown as comprising bottom-elements generally indicated at 30 that extend across areas in rear of respective retort-bodies, and ridge elements, generally indicated at 31, that extend across areas in rear of the tuyères bordering the retort bodies.

Each bottom structure 30 is composed of a plurality of identical plate-units 33 of special construction, each comprising a body-web 34 and, along the top and rear edges of the body a marginal head or thickened border which, when the plates are assembled side-by-side, affords the generally-solid surfaces of the structure, while the body-webs 34, being relatively narrow, divide the interior of the structure into a series of longitudinally extending spaced ribs with intervening air passages 36, these being open through the under side of the structure. The generally-solid portion or marginal shell of this bottom formation preferably presents a top surface 38 that curvingly up-slopes as at 39 from its front end of junction with the retort bodies to a curved crest somewhat in front of the center of length of the plate, from which crest it down-slopes rearwardly as at 40 to a level lower than its front end, where it meets the downwardly and forwardly inclined rear wall 41 of the plate, which extends forward to its point of support on the flange 19' of the frame member 19, these top and front walls of the plate thereby providing a rearwardly overhanging nose 42. The rocking dump plate 23, mounted on a supporting shaft 45 carried in the frame supporting bracket 46, is arranged, when closed, to stand level with this nose 42.

Each said bottom plate has upon opposite sides of its head structure suitable provision for interlocking engagement for complementary provision made in the adjoining plate, each such plate being herein shown as having on one side a tongue 48 running along portions of its rear and top walls, and with a corresponding groove 49 on its opposite side, for tongue and groove engagement of adjoining plates as shown in Fig. 5. The bottom of each rear-wall is flat, to rest on the support 19', but the front margin of each body web is provided with a lug 50 to engage in the channel 24 and with a hook 51 to pass under the channel bar and pre-

vent lifting of the front end of the plate structure.

Each plate is provided, in the lateral faces of its head, with narrow notches 57 and 58, preferably in the front up-slope and near the crest, respectively, and through the narrow air-emissive apertures thus formed in the bottom structure air may pass from the spaces 36 between the webs. This insures air circulation through these bottom structures to tend to cool them and preserve them against the attacks of the fire, and also to provide air for furtherance of combustion of partially consumed fuel in passage over the rear end structure. Such important cooling feature is furthered by the provision of lateral fins 60 on opposite sides of the body webs and of full plate-width so that fins of contiguous plates may meet, edge to edge, when the plates are in assembled relation, these fins thereby forming baffles in the air passages 36, preferably extending from points of close proximity to the body structure of the retorts in a downwardly and rearwardly inclined direction to practically the lower margin of the plates at a point sufficiently spaced from the front wall of the plates to permit of air ingress. Such baffles force the circulation of the air, in reaching the openings 57 and 58, in a path conducive to adequate cooling of the whole inner surface of the head-wall of the plates; and in themselves they add to the cooling area; and in the particular position and relation shown they serve to dump any ashes that might tend to accumulate thereon by falling through the apertures 57 and 58.

Between the separate groups of bottom-plates, the ridge structures 31 intervene. Each such ridge structure is preferably made in two sections, longitudinally split in a central vertical plane. Jointly these sectional castings provide a front trunk portion 63 forming an effective continuation of the tuyère block structure 12 intervening between retort bodies and a rear end portion 64 cooperating with and laterally adjoining the bottom structure 30. Throughout the length of the said bottom structure 30 the elevation of the ridge above the plates 33 gradually decreases from front to rear, and the rear face 65 of the ridge structure aligns with that of the bottom structure. The base portion of the ridge structure is formed with side walls 66 to fit between, and against the endmost ones of the adjacent groups of plates 33, shoulders 67 (Fig. 5) of the ridge structure overlying the adjacent margins of said endmost plates. From the side walls 66 transverse webs 68 project in such relation that the webs of the two sections may have centrally overlapping ears 69 secured together as by a bolt 70. The ridge structure preferably has, in its forward, trunk portion, tuyères 72 of relatively large ca-

pacity, and along its top surface small tuyère openings 73 formed by notches in the meeting edges of the sections, and along its line of juncture with the floor plates, shallow tuyères 74. At its front end each section of the ridge structure may be provided with a lug 75 to hook over the angle-iron 25, to assist in retaining the structure against longitudinal displacement.

10. As to an extreme retort of a battery provided in a furnace, only a single section of ridge-structure need be employed, as indicated at 31 in Fig. 2, this being supplemented by dead plates 80, and the side tuyère structure 12' of the retort may be provided with a corner block 81 of suitable design to rest on the parts 31 and 80, these detail features being not pertinent to my present invention.

20. It will be noted that the rear end structures of alternating longitudinal zones provided by the bottom plate structures 30 and the ridge structures 31, form a substantial continuation of the retort arrangement, in effect on fuel guidance and distribution, with the crested form of the upper surface of the bottom structure aiding in holding back the fuel against too-sudden delivery to the ash-pit, and with the steeply down-curved rear portion of the bottom surface facilitating final delivery of the ash to the dump plate, aided by the even steeper inclination of the rearward exposed surfaces of the ridge structure. Effective air distribution is provided, not only for maintaining combustion of such fuel as arrives at this portion of the furnace in only partly consumed condition, but to insure adequate cooling of this hard-used area of the combustion chamber floor. With the construction shown the air in passage to the tuyère openings from the wind chamber 21 contacts with large cooling surfaces provided by the webs which run longitudinally as to the bottom structure and transversely as to the rib structure; and in the bottom structure the circulation is additionally directed, and cooling assured by the provision of the baffle-fins 60. Further it will be noted that should a portion of the bottom of the rear end burn out, having its marginal wall melted along the crest portion, the closely spaced, heavy vertical webs will still carry the fire without the creation of large holes and without dumping the fire into the wind-chamber to any serious extent. The specified mounting of the plates of the bottom end sections of the ridges, in locked security at their front edges, but in flat sliding contact with the head 19' of frame beam 19 tends to prevent warping, distortion or displacement of the structure unit, for the rear end structure may expand and contract without restraint at the point of bearing on frame 19, and the entire rear end structure

can move as required by expansion of the retort body.

It will be understood that while I have herein described in considerable detail a specific embodiment of my invention, some refinements of which I may claim for their specific advantage, my invention in its broader aspects is not restricted to the precise details shown and many changes may be made therein without departure from the spirit of my invention within the scope of the appended claims.

I claim:

1. The combination of a stoker-retort, having at its rear end provision to interlock with hereinafter specified plates; a supporting member in rear of and below the rear end of said retort; and spanning between and supported in position by said support and the rear end of said retort, a sectional rear end structure comprising a plurality of relatively narrow long and deep vertical plates arranged side by side and extending lengthwise of the retort-structure and interlocking with its rear-end, each such plate having a web portion with a marginal head at its top and its rear end, said heads contacting to hold the webs in spaced relation and jointly forming a top surface in substantial continuation of the bottom of the retort and forming also a generally upright, substantially closed rear end extending down to said supporting member.

2. The combination of a plurality of stoker-retort bodies, arranged side by side and spaced apart, tuyère structures between said retort bodies, and a rear end structure comprising bottom portions aligning with the retort bodies and ridge portions aligning with the intervening tuyère structures, said ridge portions fitting between and laterally spacing the bottom portions and said bottom portions being composed each of a plurality of narrow plate-sections arranged on edge, side by side, and lengthwise of the retorts, with their top surfaces jointly forming a substantial continuation of the bottom of the retort and their rear surfaces jointly forming a substantially-closed generally-upright end.

3. The combination of a plurality of stoker-retort bodies, arranged side by side and spaced apart; tuyère structures between said retort bodies; and a rear end structure comprising bottom portions aligning with the retort bodies and ridge portions aligning with the intervening tuyère structures, said ridge portions fitting between and laterally spacing the bottom portions, and said bottom portions being composed each of a plurality of narrow plate-sections arranged on edge, side by side and lengthwise of the retort, with their top surfaces jointly forming a substantial continuation of the bottom of the retort and their rear surfaces jointly

forming a substantially-closed generally-upright end, the several sections of said bottom portions being identical in structure and each comprising a deep narrow web or body portion and a broader shallow head portion, said head portions contacting to maintain the body portions separated and having provision for inter-engagement of adjoining heads.

10 4. The combination of a stoker-retort having at its rear end provision to interlock with hereinafter specified plates, a supporting member in rear of and below the rear end of said retort; and spanning between 15 and supported in position by said support and the rear end of said retort, a sectional rear-end structure comprising a plurality of relatively narrow, long and deep vertical plates arranged side by side and extending 20 lengthwise of the retort-structure and interlocking with its rear-end, each such plate having a web portion with a marginal head at its top and its rear end, said heads contacting to hold the webs in spaced relation 25 and jointly forming a top surface in substantial continuation of the bottom of the retort but, in a rearward direction, up-sloping from the rear end of the retort to an intermediate crest and then down-sloping; 30 and said heads also jointly forming a rear surface which is substantially closed and slopes forwardly and downwardly from the line of juncture with the top surface to said supporting member.

35 5. The combination of a plurality of retorts arranged side by side and spaced apart and each having a body with a down-sloping margin, tuyère structures between adjoining retorts, and a rear-end structure comprising bottom portions aligning with the retorts and ridge portions aligning with the intervening tuyères, supporting means in rear of the retorts for supporting from below the rear end of the bottom portions, each 40 said bottom portion comprising a plurality of plates of relatively deep narrow construction arranged on edge, said plates having provision for interlocking with the rear extremities of the retorts, and said ridge portions comprising bodies rising higher than the bottom portions and resting on the extreme ones of adjacent groups of bottom plates and having side walls extending between said plates on which it rests.

50 6. The combination with a stoker retort having a tuyère bordered down-sloping margin, and a bottom between the tuyère-bordered sides of the retort, of a rear end structure providing a bottom portion longitudinally aligning with the bottom of the retort and comprising a plurality of narrow deep plate sections arranged on edge with the forward portions of their top surfaces forming a substantial continuation of the retort-bottom, each said plate section com-

prising a deep vertical web and a shallow marginal head for contact with the head of an adjoining section to space the vertical webs apart, and lateral fins on said body webs covering a substantial portion of the 70 otherwise open length of the bottom of the web, said fins on adjoining plates being similarly positioned jointly to form a baffle.

7. The combination of a stoker retort having at its rear end provision for plate-engagement, a support back of said retort, and a sectional rear end structure comprising a plurality of vertically disposed plates each having a web and a marginal head, 75 said heads being arranged for lateral abutment one against another to form the upper surface of the rear end structure and space said webs apart, the forward portions of 80 said plates having provision for interlocking engagement with the provision on the 85 retort-ends, and having on their heads provision for interlocking the plates one with another.

8. A rear-end plate for coaction with duplicate plates to form a rear end bottom structure for an underfeed stoker, comprising a relatively deep vertical web, a relatively shallow marginal head bordering the top surface of the web, complementary provision at opposite lateral faces of the heads 95 for interlocking the heads together, and provision at the front end of the plate for locking it to a retort.

9. A rear-end plate for coaction with duplicate plates to form a rear-end bottom-structure for an underfeed stoker and having at its front end provision for coaction 100 with a retort, comprising a relatively deep vertical web, a relatively shallow marginal head bordering the top surface of the web, laterally-extending fin structures on opposite sides of the web below the marginal head at the top of the web, said fins extending laterally to the planes of the two 105 respective sides of the head, for the purpose described.

10. A rear-end plate for coaction with duplicate plates to form a rear-end bottom-structure for an underfeed stoker and having at its front end provision for coaction 115 with a retort, comprising a relatively deep vertical web, and a relatively shallow marginal head bordering the top surface and the rear surface of said web, said parts providing a top-portion having a crest between the front and rear ends of the structure and down-sloping from said crest in both said directions but more steeply in a rearward direction, and the rear portions of said head and web extending downwardly 120 from their line of juncture with the top surface to an extent greater than the height of said crest, the top portion only of said head having marginal edge-notches therein 125 to form tuyères.

11. A rear-end plate for coaction with duplicate plates to form a rear-end bottom-structure for an under-feed stoker and having its front end shaped for coaction with a retort, comprising a relatively deep vertical web and a marginal head which is relatively shallow and borders on both sides thereof the top and rear portions of the web to provide the top and rear surfaces of the plate, said top surface having a crest nearer its forward end than its rear end and down-sloping from said crest in both said directions but more steeply in a rearward direction, and the rear surface of said plate sloping forwardly and downwardly from its line of juncture with the top surface, and said top surface only having marginal edge-notches to form tuyères.

12. A rear-end plate for coaction with duplicate plates to form a rear end bottom-structure for an underfeed stoker and having its front end shaped to provide for coaction with a retort, comprising a relatively deep vertical web, a relatively shallow marginal head bordering the top and rear por-

tions of the web on both sides thereof, and complementary provisions at opposite lateral faces of said head for interlocking the heads together; said head being of uniform lateral protrusion from the web throughout its portion at the rear end of the web and having in its portion at the top of the web lateral edge-notches to form tuyères.

13. A rear-end plate for coaction with duplicate plates to form a rear-end bottom-structure for an underfeed stoker, comprising a relatively deep vertical web, a relatively shallow marginal head bordering the top and rear end of the web and extending laterally from both sides thereof and having provision at opposite lateral faces for interlocking adjoining heads together, and said web having provision at its front end for locking it to a retort, and narrow fins on said web extending rearwardly and downwardly along opposite sides of the web beneath the front portion of said head, substantially as and for the purpose described.

ROYCE L. BEERS.
